UNITED STATES PATENT OFFICE.

CHARLES H. BOECK, OF JACKSON, MICHIGAN, ASSIGNOR TO NOVELTY MANUFACTURING COMPANY, OF JACKSON, MICHIGAN, A CORPORATION OF MICHIGAN.

DESIGN FOR A HEATER.

SPECIFICATION forming part of Design No. 37,085, dated August 9, 1904.

Application filed January 16, 1904. Serial No. 189,219. Term of patent 14 years.

all whom it may concern:

Be it known that I, CHARLES H. BOECK, a citizen of the United States, residing at Jackson, in the county of Jackson and State of Michigan, have invented a new, original, and ornamental Design for Heaters, of which the following is a specification, reference being had to the accompanying drawings, forming a part thereof.

Figure 1 is a side elevation of a heater, show-

ing my new design; and Fig. 2 is a top plan view of the same.

I claim as new and desire to secure by Letters Patent of the United States—

The ornamental design for a heater substantially as herein shown.

CHARLES H. BOECK.

Correction in Design Letters Patent No. 37,085

It is hereby certified that in Letters Patent No. 37,085, granted August 9, 1904, upon the application of Charles H. Boeck, of Jackson, Michigan, for a "Design for a Heater," an error appears in the printed specification requiring correction, as follows: Lines 10-12, the description of the figures should be stricken out and the sentence, *The figure is a perspective view showing the design of the heater*, should be inserted instead; and that the said Letters Patent should be read with this correction therein that the same may conform to the record of the case in the Patent Office.

Signed and sealed this 6th day of September, A. D., 1904.
